(57) **CLAIM**

The ornamental design for a segmented bed support leg, as shown and described.

DESCRIPTION

FIG. 1 is an exploded perspective view showing the top and front side of our new design.

FIG. 2 is an exploded front side elevation view thereof;

FIG. 3 is a top plan view thereof;

FIG. 4 is a bottom plan view thereof; and,

FIG. 5 is an elevation view of a segmented bed support leg, showing our new design.

The rear elevation view and the right and left side elevation views are identical to the front elevation view of FIG. 2.
